UNITED STATES PATENT OFFICE.

CHARLES H. NAPIER, OF MACON, GEORGIA.

TARGET-THROWING DEVICE.

1,353,663.

Specification of Letters Patent. Patented Sept. 21, 1920.

Application filed February 6, 1920. Serial No. 356,763.

To all whom it may concern:

Be it known that I, CHARLES H. NAPIER, a citizen of the United States of America, and a resident of Macon, county of Bibb, State 5 of Georgia, have invented certain new and useful Improvements in Target-Throwing Devices, of which the following is a specification.

The main objects of this invention are to 10 provide an improved device for throwing targets of the type generally known as clay pigeons; to provide an improved arrangement of the two relatively moving parts by which the throwing is effected; to provide 15 improved means for imparting a revolving or whirling motion to the target as it is discharged so as to cause it to sail; to provide improved mechanism for actuating the movable part of said device; and to provide an 20 improved construction and arrangement of the parts of a device of this kind, whereby it may be conveniently used in the hands of a person in a manner similar to that in which a gun is used.

25 An illustrative embodiment of this invention is shown in the accompanying drawings, in which—

Figure 1 is a perspective view of the improved target throwing device.

30 Fig. 2 is a longitudinal sectional detail.

Fig. 3 is an enlarged transverse sectional detail taken on the line 3—3 of Fig. 2, the target discharging member being shown in its retracted position preliminary to being 35 released for discharging a target.

Fig. 4 is an enlarged detail of the friction-surfaced roller carried by the target discharging member.

In the specific embodiment herein illustrated, the device comprises a supporting member 1, a target discharging member 2, and impelling mechanism 3.

The supporting member 1 is preferably made up of two similarly constructed parts 45 4 and 5, the opposed faces of which are suitably recessed and cut away so as to provide a vertically disposed guideway 6 for the target discharging member 2 and a recess 7, separated from the guideway 6 by a partition 8, for housing the impelling mechanism 3. Grooves 9 and 10 are formed in the opposed faces of the respective parts 4 and 5 and located slightly below the top of the member 1 so as to provide runways for supporting rollers 11 on the target discharging member 2. The outer end of the guideway

6 below the grooves 9 and 10 and the recess 7 are closed by a block 12, and the rear ends thereof are closed by a handle 13.

A ledge or plate 14 is secured to one side 60 of the member 1 so that the upper face 15 thereof coacts with the top of the parts 4 and 5 to provide a flat surface over which the target is caused to travel in being discharged from the device. A guide rail or 65 flange 16 extends along the edge of the plate 14 substantially parallel to the guideway 6. A strip of friction material 17, preferably rubber, is secured to the guide rail 16 so as to extend inwardly therefrom in spaced 70 relation to the face 15 of the ledge 14.

The target discharging member 2, as herein shown, is in the form of a metal block having rollers 11 secured to the sides thereof and received in the grooves 9 and 10, whereby the member is reciprocatingly mounted in the guideway 6. A roller 18 is secured on the top of the member 2 and has a band of friction material 19, preferably rubber, secured to the periphery thereof. A 80 shoulder 20 is formed on the under side of the target discharging member 2, which is adapted to engage a shoulder 21 on the trigger 22 when said discharging member is drawn back to the rear end of the guideway 85 6. A suitable spring 23 normally shifts the trigger 22 to bring the shoulder 21 into position to engage the shoulder 20 on the discharging member 2. A clip or finger hold 24 is provided on the member 2 rearwardly 90 of the roller 18, by which the discharging member 2 is moved into its retracted position.

The impelling mechanism for the target discharging member 2 comprises a cable 25, 95 pulleys 26 and 27, and a resilient member 28. The cable 25 extends around the pulley 26 located adjacent to the forward end of the member 1 below the guideway 6 and has the outer end 29 thereof secured to the target discharging member 2. The main portion of the cable is doubled upon itself in the recess 7 and has the end 30 thereof connected to the member 1 near the pulley 26. The pulley 27 is located in the loop formed 100 by the doubling of the cable upon itself. The member 28 is preferably in the form of a rubber band looped through a yoke 31 connected to the pulley 27 and having the ends secured to pins or shoulders 32 within 105 the member 1 near the trigger 22. This arrangement of the cable requires the resilient

member 28 to stretch only half the distance which the target discharging member 2 is required to travel and thereby doubles the effectiveness of the resilient member 28.

5 The handle 13 is shaped so as to be conveniently held in one hand and the under side of the member 1 is shaped so as to rest conveniently in the palm of the other hand, the under side of the ledge 14 being also 10 shaped so as to conveniently rest against the thumb and adjacent portion of said other hand, thus enabling one to hold the device in the hands and use it in a manner similar to that in which a gun is used.

15 The device herein shown and described is operated substantially in the following manner:

By means of the finger clip 24 the target discharging member 2 is drawn to the rear 20 end of the guideway 6 until the shoulders 20 and 21 engage, whereupon the member 2 is held in its retracted position. A target 33 is then placed upon the member 1 and ledge 14 with the rim 34 bearing against the friction 25 rim 19 of the roller 18 and located under the rubber strip 17 and the periphery 35 resting against the edge of said strip.

With the device held in the hands like a gun the trigger 22 is retracted so as to disengage the shoulders 20 and 21, whereupon the discharging member 2 is shot out to the end of the guideway 6. As the target 33 is carried along the member 1 and ledge 14, it is given a rotating movement by reason of its 30 contact with the friction strips 17 and 19, so that upon being discharged, it tends to sail through the air.

Although but one specific embodiment of this invention has been herein shown and described, it will be understood that numerous details of the construction shown may be altered or omitted without departing from the spirit of this invention as defined by the following claims.

45 I claim:

1. A target throwing device, comprising a support providing a flat surface over which a target may be caused to travel, a guide rail extending along said surface, a target discharging member adapted to move a target over said surface for discharging the same from said device, and friction means on said rail adapted to contact with the target and cause the rotation thereof during its travel over said surface.

2. A target throwing device, comprising a support providing a flat surface over which a target may be caused to travel, a guide rail extending along said surface, a target discharging member adapted to move a target over said surface for discharging the same from said device, and a strip of rubber secured to said rail and extending outwardly therefrom and spaced away from said surface and adapted to contact with the target

and cause the rotation thereof during its travel over said surface.

3. A target throwing device, comprising a support providing a flat surface over which a target may be caused to travel, a guide rail 70 extending along said surface, a target discharging member adapted to move a target over said surface for discharging the same from said device, and friction means on said rail and said discharging member adapted to 75 contact with the target and coat therewith and with each other to cause the rotation thereof during the travel along said surface.

4. A target throwing device, comprising a support providing a flat surface over which 80 a target may be caused to travel, a guide rail extending along said surface, a target discharging member adapted to move a target over said surface for discharging the same from said device, a strip of rubber secured to said rail and extending outwardly 85 therefrom and spaced away from said surface and adapted to contact with the target, and a rotatable part on said member having a friction surface also adapted to contact 90 with the target and hold the same in contact with said strip and coat therewith and with said strip of rubber to cause the rotation of the target during its travel over said first-mentioned surface.

5. A target throwing device, comprising a support providing a flat surface over which a target may be caused to travel, a target discharging member movable along said surface for discharging a target from said device, a 100 cable doubled upon itself and having one end connected to said member and the other end to said support, a pulley located in the loop formed by the doubling of said cable, and resilient means connected to said pulley and 105 said support adapted to provide the power for moving said member.

6. A target throwing device, comprising a support providing a flat surface over which a target may be caused to travel, a target discharging member movable along said surface for discharging a target from said device, a stationary pulley located at the outer end of 110 said surface, a cable extending partly around said pulley and having the end thereof connected to said member, said cable being doubled upon itself and having the other end secured to said support adjacent to said pulley, a second pulley located in the loop formed by the doubling of said cable, and 115 resilient means connected to said second pulley and said support and adapted to provide the power for moving said member.

7. A target throwing device, comprising a member, a ledge arranged on one side of 120 said member and coacting with the top of said member to provide a surface over which a target may be caused to travel, said member having a vertically disposed guideway arranged therein and having grooves 125

- formed at the sides of said guideway, a block having means on the sides thereof extending into said grooves for slidably supporting said block in said guideway, a pulley located in said member adjacent the outer end thereof, a cable extending partially around said pulley and having one end thereof connected to said block, and a resilient member connected to said support 5 and to said cable and adapted to provide the power for moving said block outwardly along said guideway for discharging a target from said device.
8. A target throwing device, comprising a member, a ledge arranged on one side of said member and coacting with the top of said member to provide a surface over which a target may be caused to travel, said member having a vertically disposed guideway arranged therein and having grooves formed at the sides of said guideway, a block having means on the sides thereof extending into said grooves for slidably supporting said block in said guideway, a pulley located in said member adjacent the outer end thereof, a cable extending partially around said pulley and having one end thereof connected to said block, said cable extending rearwardly from said pulley below said guideway and being doubled upon itself and extending forwardly and having the other end thereof connected to said support adjacent to said pulley, a second pulley located in the loop formed by the doubling of said cable, and resilient means connected to said pulley and to said support and adapted to provide the power for moving said block outwardly along said guideway to discharge a target from said device.
9. A target throwing device, comprising a member, a ledge arranged on one side of said member and coacting with the top of said member to provide a surface over which a target may be caused to travel, said member having a vertically disposed guideway arranged therein and having grooves formed at the sides of said guideway, a block having means on the sides thereof extending into said grooves for slidably supporting said block in said guideway, a pulley located in said member adjacent the outer end thereof, a cable extending partially around said pulley and having one end thereof connected to said block, a resilient member connected to said support and to said cable and adapted to provide the power for moving said block outwardly along said guideway for discharging a target from said device, a handle secured to the other end of said member, and a trigger arranged adjacent to said handle and normally urged to engage said block and hold the same in its retracted position preparatory to its being released to cause the discharge of a target.
10. A target throwing device, comprising a support, a ledge secured to one side of said support and coacting with the top thereof to provide a flat surface over which a target may be caused to travel, a guide rail extending along one edge of said ledge, a target discharging member reciprocatingly mounted on said support so as to travel substantially parallel to said rail, and means for normally urging said discharging member toward the outer end of said support.
11. A target throwing device, comprising a member, a ledge arranged on one side of said member and coacting with the top of said member to provide a surface over which a target may be caused to travel, a guide rail extending along one edge of said ledge, said member having a vertically disposed guideway arranged therein and having grooves formed at the sides of said guideway, a block having means on the sides thereof extending into said grooves for slidably supporting said block in said guideway, a pulley located in said member adjacent the outer end thereof, a cable extending partially around said pulley and having one end thereof connected to said block, a resilient member connected to said support and to said cable and adapted to provide the power for moving said block outwardly along said guideway for discharging a target from said device, a strip of rubber secured to said guide rail so as to form a friction surface adapted to contact with the target, and a rotatable part mounted on said block and having a friction surface adapted to contact with a target and coact therewith and with said rubber strip during the movement of said target along said surface to impart a revolving motion to the target.
12. A target throwing device, comprising a support, a ledge secured to one side of said support and coacting with the top thereof to provide a flat surface over which a target may be caused to travel, a guide rail extending along one edge of said ledge, a target discharging member reciprocatingly mounted on said support so as to travel substantially parallel to said rail, means for normally urging said discharging member toward the outer end of said support, a handle secured to the other end of said member, and a trigger arranged adjacent to said handle and normally adapted to hold said member in its retracted position preparatory to its being released to cause the discharge of a target.

Signed at Chicago this 3d day of February, 1920.

CHARLES H. NAPIER.
